UNITED STATES PATENT OFFICE.

GERARD JOHAN LUGT, OF AMSTERDAM, NETHERLANDS.

DOUBLE-ACTING INTERNAL-COMBUSTION ENGINE.

Application filed December 3, 1921. Serial No. 520,081.

To all whom it may concern:

Be it known that I, GERARD JOHAN LUGT, a subject of the Queen of the Netherlands, residing at Amsterdam, Netherlands, have invented certain new and useful Improvements in and Relating to Double-Acting Internal-Combustion Engines, of which the following is a specification.

The application of the double-acting principle to Diesel-engines presents various difficulties. Notably the stuffing-box of the piston-rod which has to withstand high pressures and temperatures is liable to give trouble and may be a cause of dangerous unreliability. It is already a difficult problem in many cases to arrange all the valves on the top-cylinder-cover of a Diesel-engine and this difficulty is still increased in the case of a double-acting engine by the piston-rod, piercing the cylinder-cover just there, where the fuel-injection valve should be placed to insure a good combustion.

All these difficulties can be overcome by increasing the volume of the compression space of the bottom side of the cylinder so much, that the combustion can take place in a special combustion chamber, located outside of the circumference of the cylinder, in which also the valves will be put. The compression space being so much larger than that at the top side, the compression end pressure will be appreciably less; by injecting only a relatively small quantity of fuel, which means working with a larger surplus of air, i. e. with a lower medium pressure, the medium temperature of the cycle can be kept so low that piston and piston rod work under absolutely safe conditions.

According to the present invention a double-acting internal combustion engine has a considerable higher compression on the side opposite to the crank (topside) than on the side of the crank (bottom side). The top side will be more specially a Diesel engine, and the bottom side a medium pressure engine.

It is known that the compression-ratio in a Diesel-engine is so chosen that even in a cold engine self-ignition will take place, but that the compression could be much lower when the engine is warm. The compression-ratio on the bottom side can be taken so that self-ignition will just take place when the engine is hot, which, however, does not exclude the use of special means for igniting the charge, f. i. incan-

descent plates, igniting plugs, electrical coils or sparks.

An engine according to this invention has many important advantages. The single-acting Diesel-engine (top side) can be constructed exactly in the same way as usual, with piston-rod and crosshead. Evidently the engine can work with the top side only, and the bottom side may be heated up before being put to work. This pre-heating can be done very effectfully by means of the exhaust-gases of the top side, which are lead to the bottom side through a branch on the exhaust-pipe. It is also possible to mix a certain percentage of hot exhaust-gases with the cold combustion air of the bottom side, in order to increase the end temperature of the compression at the bottom side, without needing a high ratio of compression. Also the combustion air may be pre-heated (without mixing) by means of exhaust gases, either from the same cylinder or from some other cylinder, or either from the Diesel part or from the medium pressure part of the engine. Thus self-ignition is rendered possible with a low compression, where generally special igniting devices would be necessary. As, for getting the bottom side started, it is necessary to use exhaust gases from the top side, the branch on the exhaust pipe of the top side is to be considered a very important part of the invention. It goes without saying that in a multiple-cylinder engine the exhaust gases of any top side cylinder may be used for any bottom side cylinder.

In a four-cycle engine the cycles on the different sides of a cylinder may be thus arranged, that the combustion and expansion stroke on the top side coincide with the exhaust stroke on the bottom side of the cylinder. The bottom side working with a large excess of air, the exhaust-gases of that side ought to be practically invisible, if they are not, the piston is probably leaking or blowing through. In doubtful cases the fuel supply to the bottom side can be temporarily suspended in order to ascertain if the smoky exhaust is due to leaking of the piston.

If the engine is a reversible one, e. g. a marine engine, it will be sufficient only to fit the top side with a reversing mechanism, when running astern the bottom side can be put out of action by lifting all the valves and by shutting off the fuel supply. Also

the starting device will only be fitted to the top side of the engine. The valve mechanism is thus very much simplified, which is of special importance, as the bottom side is usually rather crowded.

It is therefore the Diesel part (top side of the engine) which keeps the engine ready for use and reliable under all circumstances; the medium-pressure part (bottom side) increases the capacity and the mechanical efficiency, without affecting the simplicity of the engine to a considerable extent.

The oil-rests which are collected in a single-acting engine in an oiltray underneath the cylinder, can be easily removed out of the double-acting cylinder according to the invention by opening a relief valve in the bottom cover.

The pressure in the cylinder during expansion and compression stroke will then push the oil-rests out.

The invention is for the purposes of the present description illustrated in the accompanying drawings, in which:

25. The figure is a diagrammatic view of a portion of an internal combustion engine, illustrating the invention.

The cylinder 1 shows an upper cover 2, provided with a sprayer 3 and an inlet valve 30 5 and an outlet valve 4 of the ordinary Diesel type. Through the lower cover 6 and the stuffing box 7 the piston rod 8 passes. The lower side of the cylinder 1 is provided with the compression chamber 9 bearing the seats 35 for the inlet valve 10 and the outlet valve 11.

The exhaust piping 12 of the Diesel-side of the cylinder shows a branch 13, provided with a stop valve 14 and leading to the inlet valve 10. Along the same valve 10 air may be drawn from the space between the heating mantle 15 and the other exhaust pipe 16 through the branch 17, the latter being provided with a butterfly valve 18. For the sake of increasing the pre-heating 45 of the air in the space between the exhaust tube 16 and the mantle tube 15 a direct connecting tube 19 between the exhaust pipes 12 and 16 may be provided, so that also the heat of the exhaust gases of the Diesel-side 50 may be used in pre-heating the air drawn into the lower part of the cylinder.

What I claim as my invention is:—

1. In a double-acting internal combustion piston engine the cylinder side opposite the crank having a higher ratio of compression than the crank side of the cylinder.

2. In a double-acting internal combustion piston engine having on the cylinder side op-

posite the crank a higher ratio of compression than on the crank side, the compression ratio on the crank side being high enough to insure self-ignition.

3. In a double-acting internal combustion piston engine having on the cylinder side opposite the crank a higher ratio of compression than on the crank side, the compression ratio on the crank side being high enough to insure self-ignition when the cylinder is hot.

4. In a double-acting internal combustion piston engine having on a cylinder side opposite the crank a higher ratio of compression than on the crank side, a connection between the exhaust piping of the side opposite the crank with the air-inlet piping of the crank side of a cylinder.

5. In a double-acting internal combustion piston engine having on the cylinder side opposite the crank a higher ratio of compression than on the crank side, means for heating the combustion air for the crank side of the cylinder with the aid of combustion gases.

6. In a double-acting internal combustion piston engine having on the cylinder side opposite the crank a higher ratio of compression than on the crank side, means for heating the combustion air for the crank side of the cylinder with the aid of combustion gases, and the compression ratio on the crank side being high enough to insure self-ignition.

7. In a double-acting internal combustion piston engine having on the cylinder side opposite the crank a higher ratio of compression than on the crank side, means for heating the combustion air for the crank side of the cylinder with the aid of combustion gases, and the compression ratio on the crank side being high enough to insure self-ignition when the cylinder is hot.

8. In a double-acting internal combustion piston engine working on the four-cycle principle the cycles being so timed that the combustion and expansion stroke of the cylinder side opposite the crank coincides with the exhaust stroke of the side near the crank.

9. In a double-acting internal combustion piston engine having on the cylinder side opposite the crank a higher ratio of compression than on the crank side, a reversing and a starting device only on the side of the cylinder opposite the crank.

In testimony whereof I affix my signature.

GERARD JOHAN LUGT.
